United States Patent Office.

JOSHUA W. BROOKS AND HENRY RUOFF, OF ASHLEY, ILLINOIS.

Letters Patent No. 93,048, dated July 27, 1869.

FRUIT-DRIER.

The Schedule referred to in these Letters Patent and making part of the same.

To all whom it may concern:

Be it known that we, JOSHUA W. BROOKS and HENRY RUOFF, of Ashley, in the county of Washington, and State of Illinois, have invented a new and valuable Improvement in Fruit-Driers; and we do hereby declare that the following is a full, clear, and exact description of the construction and operation of the same, reference being had to the annexed drawings, making a part of this specification, and to the letters and figures of reference marked thereon.

Figure 1, of the drawings, is a representation of a front sectional view of our invention.

Figures 2 and 3 are details.

Our invention relates to fruit-driers; and

It consists, mainly, in a novel arrangement of devices intended to serve as efficient means for the purpose mentioned.

We construct our fruit-drier in the form of a small house, open both at front and rear, with double doors, for closing such openings when desirable, and a roof, having a proper inclination for carrying off the rain, and which, at the same time, serves as a reflector of heat. This roof is marked A on the drawings, and inclines downward from the centre, both in front and rear, like the roof of an ordinary house.

The doors of our drier are represented by the letter B of the drawings. They are respectively made in a concave and convex form, as represented, the concave sides being placed inward. These doors serve as reflectors of heat, in addition to the usual functions of doors.

We arrange shelves in our drier to receive the fruit, and arrange them at suitable distances from each other

on proper cleats. Some of these shelves are shown on the drawings by the letters c.

The letter d, of the drawings, represents an aperture in the front part of the roof, and we make a similar aperture in the rear part thereof. These openings are opened or closed by any suitable means, when desirable so to do. A small pivoted button would answer well for that purpose.

The letter D represents a fire-place, and letter E, a pipe leading therefrom twice across the drier, in the manner shown, and, finally, through the roof.

Figure 2 represents the front end or door of the fire-place, which may be opened or closed in the ordinary way, and

Figure 3, the bottom or grate of said fire-place.

Our fruit-drier is constructed mainly of metal, although bricks may be advantageously used for the bed or floor thereof.

The inner surface of the concave doors and roof should be of highly-polished metal, such as tin or brass.

What we claim as our invention, and desire to secure by Letters Patent, is—

A fruit-drier, having reflecting roof A, reflecting doors B, fire-place D, and pipe E, constructed and arranged substantially as specified.

In testimony that we claim the above, we have hereunto subscribed our names, in the presence of two witnesses.

JOSHUA W. BROOKS.
HENRY RUOFF.
